UNITED STATES PATENT OFFICE

2,010,370

CONVERSION OF HYDROCARBON OILS

Jacque C. Morrell, Chicago, Ill., assignor to Universal Oil Products Company, Chicago, Ill., a corporation of Delaware

Application October 24, 1933, Serial No. 694,971

13 Claims. (Cl. 196—60)

This invention relates to an improved process and apparatus for the fractional distillation of hydrocarbon oils of relatively wide boiling range, such as crude petroleum, for example, for the recovery of their desirable low-boiling fractions and separation of the intermediate and high-boiling fractions accompanied by pyrolytic conversion of the intermediate and high-boiling fractions under independently controlled conditions of elevated temperature and superatmospheric pressure, together with various selected intermediate conversion products of the process.

The advantages of separating oils of relatively wide boiling range, which are to be subjected to pyrolytic conversion for the production of high yields of good quality motor fuel, into selected low-boiling and high-boiling fractions and separately subjecting each fraction to independently controlled conversion conditions are now well recognized. The best conditions for obtaining high yields of motor fuel of high anti-knock value from low-boiling oils are ordinarily more severe than those to which higher boiling oils may be subjected without the danger of high losses, due to the excessive formation of coke and/or gas. It is also fairly well established that while high yields of motor fuel are obtainable from relatively high-boiling oils at fairly low temperatures, the anti-knock value of the motor fuel produced is ordinarily inferior to that obtainable from lower boiling oils under more severe conversion conditions.

In the present invention the advantages of selective cracking are obtained by separating the components of the charging stock which are not of satisfactory motor fuel characteristics, particularly with respect to their anti-knock value, as well as intermediate conversion products of the process boiling above the range of the desired final motor fuel product, into selected low-boiling and high-boiling fractions and subjecting the low-boiling fractions to independently controlled more severe conversion conditions than those employed for the conversion of the high-boiling fractions and, as a further step in the process, the vaporous products resulting from the relatively mild conversion of said high-boiling fractions are subjected to further conversion, together with said low-boiling fractions, whereby the anti-knock value of the motor fuel components of the vapors resulting from said relatively mild conversion of the high-boiling fractions is materially improved without excessively altering their boiling range and additional yields of good quality motor fuel are obtained from the some-

what higher boiling components of the vapors.

I have found that, by careful selection of the intermediate fractions of the charging stock and the low-boiling components of the intermediate conversion products of the process, which are to be subjected to more severe conversion conditions than those employed for conversion of the higher boiling components of the charging stock and intermediate conversion products, they may be subjected to further conversion for the production of additional high yields of motor fuel of high anti-knock value under conditions which are also suitable for the further conversion of the vaporous products resulting from the relatively mild conversion of said higher boiling oils for the purpose of improving the quality of the motor fuel components of the vapors, particularly with respect to their anti-knock value, and to produce additional yields of good quality motor fuel from the higher boiling components of the vapors. However, the nature of the low-boiling oils selected for conversion with the vaporous conversion products will vary considerably with different types of charging stocks, as will also the conversion conditions to which the commingled low-boiling oils and vaporous conversion products are subjected, and it is therefore not intended to limit the present invention to the treatment of low-boiling oils of specific characteristics nor to the use of specific conversion conditions for the treatment of the commingled vaporous conversion products and low-boiling oils, except within the range of relatively wide limits, hereinafter defined.

One specific embodiment of the present invention comprises subjecting hydrocarbon oil of relatively wide boiling range to fractional distillation whereby any desirable low-boiling components of satisfactory motor fuel characteristics are recovered and the remaining components separated into high-boiling fractions and relatively low-boiling intermediate fractions, subjecting the high-boiling fractions to conversion temperature at superatmospheric pressure in a heating coil, introducing the hot conversion products into a reaction chamber wherein the liquid and vaporous conversion products are separated, introducing the liquid conversion products from said reaction chamber into a reduced pressure vaporizing chamber, supplying the vaporous conversion products from the reaction chamber to a separate heating coil wherein they are subjected to continued conversion under independently controlled more severe conversion conditions than those to which said high-boiling

fractions are subjected, introducing the resulting products into said reduced pressure vaporizing chamber wherein a final separation is obtained between vaporous and non-vaporous conversion products, subjecting vaporous conversion products from said reduced pressure vaporizing chamber to fractionation, whereby their components boiling above the range of the desired motor fuel conversion product of the process are condensed as reflux condensate and separated into selected low-boiling and high-boiling fractions, subjecting fractionated vapors of the desired end-boiling point to condensation, collecting the resulting products, returning high-boiling fractions of the reflux condensate to the first mentioned heating coil for further conversion, together with the high-boiling fractions of the charging stock, and returning the low-boiling fractions of the reflux condensate, together with said intermediate fractions of the charging stock, to conversion, together with said vaporous conversion products from the reaction chamber.

The accompanying diagrammatic drawing illustrates one specific form of apparatus which may be utilized in carrying out my invention.

Referring to the drawing, charging stock for the process, preferably comprising an oil of relatively wide boiling range such as crude petroleum, for example, is supplied in heated state through line 1 and valve 2 to topping and fractionating column 3. The charging stock may be heated in any desired manner, not illustrated in the drawing, for example, by means of heat recovered from within the system by the use of heat exchangers or the like or by means of heat from any desired external source, prior to its introduction into column 3 and the temperature to which it is heated is sufficient to effect its substantial vaporization and fractionation in column 3, whereby it may be separated into desired low-boiling fractions, intermediate fractions and high-boiling fractions.

Any components of the charging stock boiling within the range of gasoline and of satisfactory motor fuel characteristics, particularly with respect to their anti-knock value, are withdrawn from the upper portion of column 3 through line 4 and may pass through line 5 and valve 6 to be subjected to condensation and cooling in condenser 7, from which the resulting distillate and gas pass through line 8 and valve 9 to collection and separation in receiver 10, or if desired, the low-boiling fractionated vapors from column 3 may pass through valve 11, in line 4, into line 49 to commingle therein with fractionated vaporous conversion products of the process and subjected to condensation and collection therewith, as will be later more fully described. Any uncondensable gas produced by the topping operation may be withdrawn from receiver 10 through line 12 and valve 13. The distillate recovered may be withdrawn from receiver 10 through line 14 and valve 15 to storage or to any desired further treatment. If desired, a regulated portion of the distillate collected in receiver 10 may be recirculated, by well known means not shown in the drawing, to the upper portion of column 3 to serve as a refluxing and cooling medium to assist fractionation of the vapors in this zone and to maintain the desired vapor outlet temperature, thus regulating the end-boiling point of the light distillate product recovered from column 3.

Intermediate fractions of the charging stock, including any components of the charging stock

boiling within the range of gasoline but of inferior motor fuel characteristics, particularly with respect to their anti-knock value, as well as, if desired, somewhat higher boiling components of the charging stock such as naphtha, kerosene or kerosene distillate, light gas oil and the like or suitable fractions or combinations of such materials, are withdrawn from any suitable intermediate point or points in column 3, for example, through line 16 and valve 17 to pump 18 by means of which they are supplied through line 19, valve 20 and lines 62 and 37 to conversion in heating coil 39, as will be later more fully described.

High-boiling fractions of the charging stock, including its components boiling above the range of the selected intermediate fractions supplied, as already described, to heating coil 39, are withdrawn from the lower portion of column 3 through line 22 and valve 23 to pump 24 by means of which they are supplied through line 25 and valve 26 to conversion in heating coil 27.

Heating coil 27 is located within a furnace 28 of any suitable form, by means of which the oil supplied to this zone is heated to the desired conversion temperature, preferably at a substantial superatmospheric pressure, and the heated materials are discharged from the heating coil through line 29 and valve 30 into reaction chamber 31.

Chamber 31 is also preferably maintained at a substantial superatmospheric pressure, which may be substantially the same or somewhat lower than the pressure employed at the outlet from heating coil 27, depending upon the degree of vaporization desired in this zone. Liquid conversion products which remain unvaporized in chamber 31 are withdrawn therefrom through line 32 and valve 33 and are introduced into vaporizing chamber 45, which is preferably operated at a substantially reduced pressure relative to that employed in chamber 31. Vaporous conversion products are separately withdrawn from the upper portion of chamber 31 through line 34 and may pass through valve 35, in this line, to pump or compressor 36 by means of which they are supplied through line 37 and valve 38 to further conversion in heating coil 39 or, in case a relatively high superatmospheric pressure is employed in chamber 31, suitable for further conversion of the vapors in heating coil 39, as is preferably the case, pump 36 may be bypassed by means of line 40 and valve 41.

A furnace 42 of any suitable form supplies the required heat to the oils passing through heating coil 39 to bring them to the desired conversion temperature, preferably at a substantial superatmospheric pressure, although if desired, pressures down to substantially atmospheric may be employed at the outlet from heating coil 39. However, in all cases, a higher conversion temperature and, in general, more severe conversion conditions are employed for the treatment of the oils supplied to heating coil 39 than those to which the higher boiling oils are subjected in heating coil 27.

The highly heated conversion products from heating coil 39 pass through line 43 and valve 44 into vaporizing chamber 45. Preferably, when a substantial superatmospheric pressure is employed in heating coil 39 the pressure employed in vaporizing chamber 45 is substantially reduced relative to the outlet temperature from the heating coil in order to cool and retard further conversion of the products from this zone. Introduction of the liquid conversion products from cham-

ber 31 into line 43, as illustrated, will also serve as a means of partially cooling and retarding conversion of the heated products from heating coil 39 and as a means of heating the liquid conversion products from chamber 31 to assist their further vaporization in chamber 45. It is also within the scope of the invention, although not illustrated in the drawing, to separately introduce the conversion products from heating coil 39 and the liquid conversion products from chamber 31 into vaporizing chamber 45, particularly in case appreciable further conversion of the latter in this zone is not desired.

Vaporizing chamber 45, in the case here illustrated, comprises the lower portion of vaporizing and fractionating column 21, although it is specifically within the scope of the present invention to employ one or a plurality of separate vaporizing chambers wherein the desired degree of further vaporization of the liquid conversion products from both chamber 31 and heating coil 39 may be accomplished. In the case here illustrated, residual liquid conversion products remaining unvaporized in chamber 45 may be withdrawn from the lower portion thereof through line 46 and valve 47 to cooling and storage or to any desired further treatment. It is, however, specifically within the scope of the present invention to produce substantially dry coke as the only residual conversion product of the process, in which case a plurality of coking chambers, not illustrated, are preferably employed instead of chamber 45 and may be simultaneously operated or, preferably are alternately operated, cleaned and prepared for further operation.

Vaporous conversion products pass from chamber 45, in the case here illustrated, through a riser 48 to the upper portion of column 21, wherein they are subjected to fractionation for the formation of reflux condensate comprising the components of the vapors boiling above the range of the desired motor fuel conversion product of the process.

Fractionated vapors of the desired end-boiling point are withdrawn from the upper portion of column 21 through line 49 and valve 50 and are subjected to condensation and cooling in condenser 51, either alone or together with the low-boiling vaporous components of the charging stock, supplied to line 49 as previously described. The resulting distillate and uncondensable gas passes through line 52 and valve 53 to collection and separation in receiver 54. Uncondensable gas may be released from the receiver through line 55 and valve 56. The distillate may be withdrawn from receiver 54 through line 57 and valve 58 to storage or to any desired further treatment. When desired, a regulated portion of the distillate collected in receiver 54 may be recirculated by well known means, not shown in the drawing, to the upper portion of column 21 to serve as refluxing and cooling medium to assist fractionation of the vapors in this zone and to maintain the desired vapor outlet temperature from the fractionator, thus controlling the end-boiling point of the final motor fuel conversion product of the process.

The reflux condensate formed, as previously described, in fractionator 21 is separated into selected low-boiling and high-boiling fractions. The low-boiling fractions comprise materials boiling above the range of the desired motor fuel conversion products removed as the overhead stream of fractionated vapors from column 21, the end-boiling point of which motor fuel product may

range, for example, from 350 to 437° F., or thereabouts, and the low-boiling fractions may, if desired, include materials boiling as high as 500 to 650° F., for example. The selected low-boiling fractions are withdrawn as one or a plurality of suitable side streams from column 21, for example, through line 59 and valve 60, to pump 61 by means of which they are returned through line 62, valve 63 and line 37 to further conversion in heating coil 39, together with the vaporous conversion products from chamber 31.

Components of the reflux condensate formed in fractionator 21, boiling above the range of the selected low-boiling fractions supplied to heating coil 39, as hereinbefore described, may be withdrawn from the lower portion of the fractionating section of the column through line 64 and valve 65 to pump 66 by means of which they are returned through line 67, valve 68 and line 25 to further conversion in heating coil 27, together with high-boiling fractions of the charging stock from column 3.

In an apparatus such as illustrated and above described, the preferred operating conditions may be approximately as follows: any desired pressure from substantially atmospheric or sub-atmospheric to a superatmospheric pressure of 200 pounds, or more, per square inch may be employed in the topping and fractionating stage of the process and the temperature to which the charging stock is subjected, to accomplish its fractional distillation, may range, depending upon the character of the charging stock, the pressure conditions employed and the desired separation, for example, from 400 to 600° F., more or less. The temperature employed for conversion of the high-boiling fractions of the charging stock and high-boiling fractions of the reflux condensate, measured at the outlet from the heating coil to which they are supplied, may range, for example, from 800 to 950° F., or thereabouts, and preferably a superatmospheric pressure is employed at this point in the system of the order of 100 to 500 pounds per square inch. Substantially the same or somewhat reduced pressure may be employed in the succeeding reaction chamber and a substantially reduced pressure relative to that employed in the reaction chamber is preferred in the succeeding vaporizing chamber to which liquid conversion products from the reaction chamber are supplied. The heating coil to which vaporous products from the reaction chamber, intermediate fractions of the charging stock and low-boiling fractions of the reflux condensate are supplied may utilize an outlet conversion temperature ranging, for example, from 900 to 1050° F., and any desired pressure ranging from substantially atmospheric to 1000 pounds, or thereabouts, per square inch may be employed at the outlet from this heating coil, a substantial superatmospheric pressure being preferred. The fractionating, condensing and collecting portions of the cracking system may employ pressures either substantially equalized with or somewhat reduced relative to the pressure employed in the vaporizing chamber.

As a specific example of one of the many possible operations of the process as it may be practiced in an apparatus such as illustrated and above described: The charging stock is a Mid-Continent crude of about 38° A. P. I. gravity, containing approximately 35% of 437° end-point gasoline. The crude oil is subjected to fractional distillation whereby its components, boiling up to about 250° F., which comprise approximately

12% of the crude and are of satisfactory anti-knock value, are recovered. Intermediate fractions of the charging stock, boiling between approximately 250 to 550° F., and comprising about 5 38% of the charging stock are subjected to a conversion temperature of approximately 980° F., at a superatmospheric pressure of about 800 pounds per square inch together with low-boiling fractions of the reflux condensate from the 10 fractionator of the cracking system and vaporous products from the reaction chamber, and the resulting products are introduced into a reduced pressure vaporizing chamber, the remaining higher boiling fractions of the charging stock 15 are subjected, together with high-boiling fractions of the reflux condensate, in a separate heating coil, to an outlet conversion temperature of approximately 920° F., at a superatmospheric pressure of about 300 pounds per square inch 20 and the heated products are introduced into a reaction chamber maintained at substantially the same pressure, wherein the resulting vaporous and liquid conversion products separate. The liquid conversion products from the reaction 25 chamber are supplied to the reduced pressure vaporizing chamber and the vaporous conversion products, as already mentioned, are subjected to conversion together with the intermediate fractions of the charging stock. Vaporous products 30 from the vaporizing chamber are subjected to fractionation whereby low-boiling and high-boiling fractions of reflux condensate are recovered, the low-boiling fractions being returned, as already mentioned, to further conversion together with the vaporous products from the reaction 35 chamber and the intermediate fractions of the charging stock, while the high-boiling fractions are subjected to further conversion, together with the high-boiling fractions of the charging stock. 40 A motor fuel product of about 400° F. end-boiling point is recovered as the overhead stream from the fractionator of the cracking system and is blended with the low-boiling fractions of the straight-run gasoline, recovered from the fractional distillation of the charging stock, as the 45 total motor fuel product of the process.

An operation such as above described, may yield per barrel of crude oil charging stock, about 50 74% of motor fuel having an anti-knock value equivalent to an octane number of approximately 70 and 12% of heavy residual liquid, the remaining 14% or thereabouts, based on the crude, being chargeable principally to uncondensable 55 gas and loss.

55 I claim as my invention:

1. In a process for the conversion of hydrocarbon oils wherein raw oil charging stock for the process is subjected to fractional distillation whereby it is separated into desirable low-boiling 60 components, which are condensed and collected, intermediate fractions and high-boiling components, the latter subjected to pyrolytic conversion, the resulting vaporous and liquid conversion products separated and said intermediate fractions of the charging stock separately subjected to pyrolytic conversion, the improvement which comprises subjecting the vaporous products resulting from the first mentioned conversion stage of the process to further conversion together with said intermediate fractions of the charging stock, separating the resulting vaporous and non-vaporous products from the last 65 mentioned conversion stage, subjecting the vapors to fractionation whereby their insufficiently converted components are con- 70

densed as reflux condensate and separated into selected low-boiling and higher boiling fractions, subjecting fractionated vapors of the desired end-boiling point to condensation, collecting the resulting products and returning the selected low-boiling fractions of the reflux condensate to the last mentioned cracking stage of the process for further conversion. 6

2. In a process for the conversion of hydrocarbon oils wherein raw oil charging stock for the process is subjected to fractional distillation whereby it is separated into desirable low-boiling components, which are condensed and collected, intermediate fractions and high-boiling components, the latter subjected to pyrolytic conversion, the resulting vaporous and liquid conversion products separated and said intermediate fractions of the charging stock separately subjected to pyrolytic conversion, the improvement which comprises subjecting the vaporous products resulting from the first mentioned conversion stage of the process to further conversion together with said intermediate fractions of the charging stock, separating the resulting vaporous and non-vaporous products from the last mentioned conversion stage, subjecting the vapors to fractionation, whereby their insufficiently converted components are condensed as reflux condensate and separated into selected low-boiling and higher boiling fractions, subjecting fractionated vapors of the desired end-boiling point to condensation, collecting the resulting products, returning the selected low-boiling fractions of the reflux condensate to the last mentioned cracking stage of the process for further conversion and returning the higher boiling fractions of the reflux condensate to further conversion in the first mentioned cracking stage of the process. 20 25 30 35

3. In a process for the conversion of hydrocarbon oils wherein raw oil charging stock for the process is subjected to fractional distillation whereby it is separated into desirable low-boiling components, which are condensed and collected, intermediate fractions and high-boiling components, the latter subjected to pyrolytic conversion, the resulting vaporous and liquid conversion products separated and said intermediate fractions of the charging stock separately subjected to pyrolytic conversion, the improvement which comprises subjecting the vaporous products resulting from the first mentioned conversion stage of the process to further conversion together with said intermediate fractions of the charging stock, separating the resulting vaporous and non-vaporous products from the last mentioned conversion stage, subjecting the vapors to fractionation, whereby their insufficiently converted components are condensed as reflux condensate and separated into selected low-boiling and higher boiling fractions, subjecting fractionated vapors of the desired end-boiling point to condensation, collecting the resulting products, returning the selected low-boiling fractions of the reflux condensate to the last mentioned cracking stage of the process for further conversion, returning the higher boiling fractions of the reflux condensate to further conversion in the first mentioned cracking stage of the process and commingling the liquid conversion products from the first mentioned cracking stage with the products from the last mentioned cracking stage, prior to their fractionation. 40 45 50 55 60 65 70 75

4. In a process for the conversion of hydrocarbon oils wherein high-boiling fractions of the raw oil charging stock for the process, separated 75

from its lower boiling components by fractional distillation, are subjected to pyrolytic conversion and the resulting vaporous and liquid conversion products separated, the improvement which comprises subjecting the vaporous conversion products to independently controlled more severe conversion conditions, separating the resulting vaporous and non-vaporous conversion products, subjecting the vapors to fractionation, whereby their insufficiently converted components are condensed as reflux condensate and separated into low-boiling and high-boiling fractions, subjecting fractionated vapors of the desired end-boiling point to condensation, collecting the resulting products, returning the high-boiling fractions of the reflux condensate to further conversion, together with said high-boiling fractions of the charging stock, and returning the low-boiling fractions of the reflux condensate to further conversion, together with said vaporous conversion products from the first described cracking stage of the process.

5. A process of the character defined in claim 4 wherein selected low-boiling fractions of the charging stock, separated from its higher boiling fractions by said fractional distillation, are subjected to conversion together with the low-boiling fractions of the reflux condensate and the vaporous conversion products from the first described cracking stage of the process.

6. A process of the character defined in claim 4 wherein the liquid conversion products from the first described cracking stage of the process are commingled with the conversion products from the last described cracking stage of the process, prior to their fractionation.

7. In a process for the conversion of hydrocarbon oils wherein raw oil charging stock for the process is subjected to fractional distillation whereby it is separated into desirable low-boiling components, which are condensed and collected, intermediate fractions and high-boiling components, the high-boiling components subjected to relatively mild conversion conditions of elevated temperature and superatmospheric pressure in a heating coil, the heated materials introduced into a reaction chamber, wherein vaporous and liquid conversion products separate, and the intermediate fractions of the charging stock subjected to more severe conversion conditions in a separate heating coil, the improvement which comprises supplying the vaporous products from the reaction chamber to the last mentioned heating coil for further conversion, together with the intermediate fractions of the charging stock, introducing the products from the last mentioned heating coil into a vaporizing chamber, wherein their vaporous and non-vaporous conversion products separate, supplying the liquid conversion products from the reaction chamber to said vaporizing chamber, whereby they are subjected to further vaporization, subjecting vaporous products from the vaporizing chamber to fractionation, whereby their insufficiently converted components are condensed as reflux condensate and separated into selected low-boiling and higher-boiling fractions, subjecting fractionated vapors of the desired end-boiling point to condensation, collecting the resulting products, returning the selected low-boiling fractions of the reflux condensate to the last mentioned heating coil for further conversion, together with the intermediate fractions of the charging stock and the vaporous products from the reaction chamber, and returning the higher boiling fractions of the reflux condensate to the first mentioned heating coil for further conversion, together with high-boiling fractions of the charging stock.

8. In a process for the conversion of hydrocarbon oils wherein raw oil charging stock for the process is subjected to fractional distillation whereby it is separated into desirable low-boiling components, which are condensed and collected, intermediate fractions and high-boiling components, the high-boiling components subjected to relatively mild conversion conditions of elevated temperature and superatmospheric pressure in a heating coil, the heated materials introduced into a reaction chamber, also maintained at substantial superatmospheric pressure, wherein vaporous and liquid conversion products separate, and the intermediate fractions of the charging stock subjected to more severe conversion conditions of elevated temperature and superatmospheric pressure in a separate heating coil, the improvement which comprises supplying the vaporous products from the reaction chamber to the last mentioned heating coil for further conversion, together with the intermediate fractions of the charging stock, introducing the products from the last mentioned heating coil into a reduced pressure vaporizing chamber, wherein their vaporous and non-vaporous conversion products separate, supplying the liquid conversion products from the reaction chamber to said vaporizing chamber, whereby they are subjected to further vaporization, subjecting vaporous products from the vaporizing chamber to fractionation, whereby their insufficiently converted components are condensed as reflux condensate and separated into selected low-boiling and higher-boiling fractions, subjecting fractionated vapors of the desired end-boiling point to condensation, collecting the resulting products, returning the selected low-boiling fractions of the reflux condensate to the last mentioned heating coil for further conversion, together with the intermediate fractions of the charging stock and the vaporous products from the reaction chamber, and returning the higher boiling fractions of the reflux condensate to the first mentioned heating coil for further conversion, together with high-boiling fractions of the charging stock.

flux condensate to the first mentioned heating coil for further conversion, together with high-boiling fractions of the charging stock.

9. A hydrocarbon oil conversion process which comprises fractionating the charging oil and separating therefrom a relatively light fraction and a heavier fraction, heating the latter to cracking temperature under pressure in a first heating zone and separating volatiles from residue, combining such volatilized hydrocarbons with said light fraction and heating the mixture in a second heating zone to higher cracking temperature than said heavier fraction in said first zone, fractionating the vapors produced by the cracking of said mixture to form relatively light and heavy reflux condensates, supplying the heavy reflux condensate to the first heating zone for heating therein in admixture with said heavier fraction of the charging oil, supplying the light reflux condensate to the second heating zone for retreatment with said mixture, and finally condensing the fractionated vapors.

10. A hydrocarbon oil conversion process which comprises partially distilling the charging oil to form a light distillate fraction and a heavier residual fraction, heating the latter to relatively mild cracking temperature and combining resultant vapors with said light fraction, heating the mixture to higher cracking temperature than said residual fraction, fractionating the cracked

- vapors of said mixture to form relatively light and heavy reflux condensates, supplying such light reflux condensate to the last mentioned heating step for retreatment with said mixture, and finally condensing the fractionated vapors.
11. A hydrocarbon oil conversion process which comprises partially distilling the charging oil to form a light distillate fraction and a heavier residual fraction, heating the latter to relatively mild cracking temperature and combining resultant vapors with said light fraction, heating the mixture to higher cracking temperature than said residual fraction, fractionating the cracked vapors of said mixture to form relatively light and heavy reflux condensates, supplying such light reflux condensate to the last named heating step for retreatment with said mixture, combining the heavy reflux condensate with said residual fraction to be heated therewith to the relatively mild cracking temperature, and finally condensing the fractionated vapors.
12. A hydrocarbon oil conversion process which comprises fractionating the charging oil and separating therefrom a relatively light fraction and a heavier fraction, heating the latter to relatively mild cracking temperature and separating resultant volatiles from unvaporized oil, combining such volatilized hydrocarbons with said light fraction and heating the mixture to higher cracking temperature than said heavier fraction, combining the heavy reflux condensate with said heavier fraction of the charging oil for heating therewith to the milder cracking temperature, and finally condensing the fractionated vapors.
- oil and separating the thus commingled materials into vapors and residue, fractionating the former to form relatively light and heavy reflux condensates, returning such light reflux condensate to the last named heating step for retreatment at the higher cracking temperature with said mixture, and finally condensing the fractionated vapors.
13. A hydrocarbon oil conversion process which comprises fractionating the charging oil and separating therefrom a relatively light fraction and a heavier fraction, heating the latter to relatively mild cracking temperature and separating resultant volatiles from unvaporized oil, combining such volatilized hydrocarbons with said light fraction and heating the mixture to higher cracking temperature than said heavier fraction, combining the heated mixture with said unvaporized oil and separating the thus commingled materials into vapors and residue, fractionating the former to form relatively light and heavy reflux condensates, returning such light reflux condensate to the last named heating step for retreatment at the higher cracking temperature with said mixture, combining the heavy reflux condensate with said heavier fraction of the charging oil for heating therewith to the milder cracking temperature, and finally condensing the fractionated vapors.
